ROLLER TOY

Wallace R. Shoup, Jr., Pittsburgh, Pa.

Application September 30, 1953, Serial No. 383,249

5 Claims. (Cl. 46—204)

My invention relates to a roller toy which may be very easily and repeatedly assembled and disassembled by a child, so that its appeal lies not only in its use as an entertaining toy but also as a safe and educative outlet for a child's natural curiosity concerning the construction of his toys.

I am aware that roller toys have been proposed before, but to my knowledge such toys embody rigid, fixed, and relatively complicated means for holding the rollers in assembled relation. Further, none is adapted to easy assembly and disassembly by the child himself.

The present toy embodies rollers and a very simple and yet effective means for holding the rollers in a desired spaced relation. The holding means includes a minimum of parts which enables even a child with little skill repeatedly to assemble and disassemble the toy within a very short time. In my toy I contemplate a unit of construction comprising three substantially parallel rollers wherein one roller is positioned above the other two and in contact therewith. At least the bottom two rollers have openings at each end. A rod stationed by the adjacent ends of the rollers has means to engage rotatively the openings of the bottom two rollers and a raised portion to engage the ends of the third roller and prevent its lateral movement with respect to the bottom two rollers. Suitable means connect the two rods to preclude substantial relative movement thereof.

The accompanying drawing discloses presently preferred embodiments wherein:

Figure 1 is a perspective view of the toy embodying just one unit of construction;

Figure 2 is an end elevation of Figure 1;

Figure 3 is a perspective view of the means for holding the rollers of Figure 1 in the assembled relation shown;

Figure 4 is a diagrammatic view of a spring which may be used in the means of Figure 3; and

Figure 5 is a perspective view of the present toy embodying a plurality of units of construction.

Referring to Figures 1 through 3, one unit of construction of the instant toy includes rollers 10, 11, and 12 positioned with roller 11 above the other two and in contact therewith. At least rollers 10 and 12 have openings 13 at each end and preferably roller 11 also has similar end openings 13a as when this unit is to be joined with other units as hereinafter explained. Rods 14 and 14a are stationed by the adjacent ends of the rollers on each side of the toy. The rods may be metal or plastic of fairly stiff stock. Each rod has turned ends to form pins 15 which rotatably engage the oversize openings 13 of rollers 10 and 12. The rods also have an inverted V-shaped bight 16 which engages the ends of roller 11 and prevents its lateral movement. Suitable means connects the rods 14 and 14a. Ordinary cord, or a wire 17 of sufficiently small gauge to be easily curled at its end on the bight 16 of the rods, or a resilient member such as the spring 18 of Figure 4 may be used for this purpose. The spring 18 has end loops 19 which may be easily caught around a side of the bight 16. In any case, the

2

connecting means may join either the backward side of the bight as in Figure 1 or the forward side as in Figure 3. A pulling cord 20 is attached around the pins engaging roller 10. For ease of assembly, this cord may have preformed end loops which merely slip around the pins. Decorative means such as spirals 21 are placed on the rollers.

The present toy may also embody a plurality of the units just described wherein the rollers are placed in superposed layers or tiers. In such a case, each roller may be common to two adjoining units. For example, in Figure 5, the parts corresponding to the unit of Figure 1 are repeated with the parts of other units added including rollers 22, 23, and 24; rods 25 and 26; and wires 27 and 28, all similar in construction to the corresponding parts first described. Rod 26 joins roller 12 with roller 24 in the first tier and prevents lateral movement of roller 23 in the second tier. Rod 25 joins roller 11 with roller 23 in the second tier and prevents lateral movement of roller 22 in the third tier. The wires 27 and 28 join rods 25 and 26, respectively, to two rods (not shown) on the other side of the toy which similarly engage the other ends of the same rollers as described in connection with the embodiment of Figure 1. Thus, roller 12 is common to the unit first described and a unit including rollers 12, 23, and 24; roller 11 is likewise common to the first unit and also to a unit of rollers 11, 22, and 23; and roller 23 is common to a unit of rollers 12, 23, and 24 and a unit of rollers 11, 22, and 23. Only the corner rollers 10, 22 and 24 are used in a single unit. If desired, the rods 14 and 26 in Figure 5 may be made as one piece, and this practice may be followed on the rods in the same tier of any multi-unit embodiment.

To assemble a unit, a user need only insert the rods 14 and 14a in the ends of two rollers after first including the pulling cord 20 about the forward pins of those rods if this assembly is the first. Thereafter, the rods are connected by a wire 17 or spring 18 and a third roller placed over and between the first two rollers. If more units are desired, they are similarly added to the construction. To disassemble the toy, the reverse procedure is followed. When the toy moves over a surface as by being pulled by the cord 20, the rollers in adjacent tiers are caused to rotate in opposite directions. The spiral 21 or other decorative means placed on the rollers thereby present a pleasing and attractive optical effect. In the embodiment of Figure 5, the rod 25 urges rollers 11 and 23 apart and therefore also urges rollers 10 and 24 away from roller 12. This construction aids in preventing the pins jointly occupying the end openings of roller 12 from binding its rotation. Further, the present flexible construction wherein no roller has a fixed relation with another roller enables the toy to ride over bumps and similar obstructions smoothly.

While the foregoing disclosure describes a presently preferred embodiment and modifications thereof, it is understood that the invention may be practiced in still other forms within the scope of the following claims.

I claim:

1. A roller toy adapted for easy assembly and disassembly including a plurality of units adapted to be associated with one another in superposed layers, each unit including three rollers with one roller positioned above the other two and in contact therewith, at least the bottom two rollers having an opening at each end, means to hold the rollers in said relation including a rod pivotally engaging said openings along each of the corresponding ends of the bottom two rollers, each rod having a raised portion engaging only with an end of the third roller, and means to connect said rods to prevent substantial relative movement of one with respect to the other.

2. A roller toy adapted for easy assembly and dis-

assembly by a child including six substantially parallel rollers, three rollers constituting a first tier with each successive tier having one less roller, at least all but the top roller having an opening at each end and the rollers of each tier contacting those of adjacent tiers, a retaining wire at each of the corresponding ends of the first two rollers of the first tier and the first roller of the second tier, another retaining wire at each of the corresponding ends of the second and third rollers of the first tier and the second roller of the second tier, a further retaining wire at each of the corresponding ends of the top three rollers, each retaining wire including turned ends to form pins which rotatably engage the end openings of the two rollers of the same tier associated with the wire, each retaining wire also having a raised medial portion to prevent lateral movement of the third roller and whereby said last mentioned retaining wire urges apart the pins of the first two mentioned retaining wires which conjointly engage the end openings of the second roller of the first tier, and means to prevent substantial relative movement of the wires associated with the same rollers with respect to each other.

3. A roller toy adapted for repetitive assembly and disassembly including three interchangeable rollers having a central opening at each end of at least two of the rollers, said rollers being adapted to be positioned with one above the other two and in contact therewith whereby rotating the bottom two rollers in one direction causes opposite rotation in the third, means to hold the rollers in said position including a wire at each of the corresponding ends of the bottom two rollers, each wire having turned ends to form pins which are rotatably engageable with the end openings of the bottom two rollers, each wire

also having an inverted V-shaped bight to make contact only with an end of the upper roller and prevent lateral movement thereof, and means to prevent substantial relative movement of the two wires, means to pull the toy, and decorative means on the rollers adapted to provide a pleasing appearance upon rotation of the same.

5 4. A toy including a plurality of substantially parallel rollers arranged in tiers and means to hold the rollers in each tier in said relation including a rod pivotally connecting said rollers along each of their corresponding ends, each rod having a raised portion making contact only with a roller of another tier and thereby preventing excess lateral movement of said roller, and means to prevent substantial movement of one rod relative to another in the same tier.

10 5. A roller toy adapted for easy assembly including a plurality of substantially parallel rollers arranged in tiers with one less roller in each succeeding tier, a rod pivotally connecting contiguous rollers of each tier at each 20 of their corresponding ends, each rod having a raised portion making engagement only with a roller disposed in a next tier and thereby to prevent excess lateral movement of said roller, and means to prevent substantial relative movement between the rods engaging the same 25 rollers.
